United States Patent Office.

M. ISADORA FINDLEY, OF NEW YORK, N. Y.

Letters Patent No. 78,367, dated May 26, 1868; antedated May 15, 1868.

IMPROVED WAIST-BELT OR GIRDLE.

The Schedule referred to in these Letters Patent and making part of the same.

TO ALL WHOM IT MAY CONCERN:

Be it known that I, M. ISADORA FINDLEY, of the city, county, and State of New York, have invented a new and useful Improvement in Waist-Belts or Girdles, of which the following is a full, clear, and exact description, reference being had to the accompanying drawing, forming part of this specification, and in which—

Figure 1 represents a waist-belt in its straight or open condition, constructed according to my improvement.

Figure 2, a view of the same closed, and

Figure 3, a transverse section thereof.

Figure 4 represents a longitudinal view of a modified construction of the belt at its ends, shown only in part, and buckle fastening the same.

Similar letters of reference indicate corresponding parts.

The nature of my invention consists in constructing metallic waist-belts or girdles for ladies', children's, and other use, with a peculiar mode of fastening the belt at its ends, by means of a detached buckle-gearing, with perforations in the ends of the belt.

Referring to the accompanying drawing, and more particularly figs. 1, 2, and 3, A represents a metallic belt, of an enamelled character, whereby it may not only be used as an ornamental or finished belt, irrespective of covering, but is free from rust, gives a smooth finish, and prevents chafing either as against the dress or ribbon made to encircle it, said metallic belt either being used in a direct or separate manner, or as a mere stiffener to a surrounding belt of ribbon or other like material. The better to prevent chafing or cutting, I turn down the edges a a' , to form hems s , and, furthermore, make the upper edge a of increased length to that of the lower one, whereby a fit in conformity with the natural shape of the body is secured without cutting or inconvenient pressure of said upper edge, to further carry out which advantage or advantages, especially as regards the fit and straight run of the belt, when made of a stiff material like metal, and which dispenses with puckering or objectionable elasticity, I prefer to make the belt straight for a short distance, at its centre, b , to conform to the spine or straight portion of the back, and straight at its ends c c' , with the remainder or connecting portions of a curvature or curvatures struck from a centre or centres which make the upper edge a convex, and the lower edge a' concave. The belt thus constructed may be variously fastened, but I select to employ a loose sliding buckle, B, provided with button or knob-shaped projections d d , constructed to fit and lock with a double-row of apertures e e in the one end, c' , of the belt, which apertures are arranged in a series along or near either edge to regulate the fit of the belt to different sizes of waist, said end, c' , of the belt passing through the slot of the buckle, and the button-shaped projections, d , to secure the lock of the belt, further passing through apertures f f , in the opposite end, c , of the buckle.

In some cases it may be preferred to construct the one end, c , of the belt, as shown in fig. 4, with a double set of apertures, f , and the opposite end, c' , of the belt with but a single row of apertures, e , while the detached or detachable buckle, B, is provided with three knob or button-shaped projections, d , and the end, c' , of the belt tapered or narrowed off to conceal the buckle under the opposite end, when the belt is fastened essentially as described with reference to figs. 1 and 2 of the drawing.

What I claim as my invention, and desire to secure by Letters Patent, is—

The detached buckle B, with its knob or button-shaped projections d , in combination with the perforated ends of the belt, for use essentially as shown and described.
